UNITED STATES PATENT OFFICE.

CHARLES E. PRICE, OF AUSTEN, WEST VIRGINIA.

TRACK FASTENING.

Application filed June 29, 1923. Serial No. 648,530.

To all whom it may concern:

Be it known that I, CHARLES E. PRICE, a citizen of the United States, residing at Austen, in the county of Preston and State of West Virginia, have invented certain new and useful Improvements in Track Fastenings, of which the following is a specification.

This invention has relation to track fastenings and is intended more particularly to provide simple, easily applied and efficient means for holding the rails of mine tracks in place. The tracks upon which mine cars travel to carry the product of the mine to the mouth thereof are laid upon uneven ground and must be capable of rapid and cheap construction, and, as ordinarily constructed, the tracks are liable to spread and cause derailment of the cars. It is the primary object of my invention to provide a tie which may be rapidly placed in position along the line of the proposed track and which will be of such construction that it will not slide either transversely or longitudinally of the track. A further object of the invention is to provide means whereby the rails will be securely held upon the ties, and a still further object of the invention is to provide a track fastening which may be employed at the joints of the rails with equal efficiency as at points intermediate the ends of a rail and which is also adaptable to securely hold a rail which may be placed upon its side to provide a short extension of the track. These stated objects, and other objects which will hereinafter incidentally appear, are attained in such a structure as is illustrated in the accompanying drawings, and the invention resides in certain novel features which will be hereinafter fully set forth.

In the drawings:

Figure 1 is a perspective view of a tie and track fastening embodying my invention;

Fig. 2 is a transverse section of the track upon the line 2—2 of Fig. 1;

Fig. 3 is a perspective view of parts of the fastening showing the same separated;

Fig. 4 is a similar view showing another form of rail-engaging member;

Fig. 5 is a bottom plan view of one end of the tie, and

Fig. 6 is a transverse section of a portion of the track showing an adaptation of the invention whereby to provide a short extension of the track.

The rails 1 are of the usual T-shaped formation, and in carrying out my invention, the bases of the rails are supported by metallic ties 2 which are constructed with depending side flanges 3 provided at their edges with a plurality of depending teeth or spurs 4 which are adapted to penetrate the ground or floor of the mine and thereby hold the ties in place. It is also desirable to provide similar spurs or teeth 5 at the ends of the tie which may penetrate the ground so that, when the tie has been once set in position, it will be prevented from moving either longitudinally or transversely of the track. The tops of the ties are flat so as to provide a firm bed or support for the rails and at the ends of the ties are provided overhanging lugs or rail-engaging plates 6 which may be short plates spaced apart, as shown in Fig. 3, or may be one continuous plate, as shown at 7 in Fig. 4. Of course, when the single continuous plate 7 is employed, the end teeth or spurs 5 will be omitted, and an advantageous arrangement is to provide the alternate ties at their opposite ends with the spurs 5 and the elongated plates 7 respectively. Near the ends of the ties, the side flanges 3 are provided with a plurality of longitudinally extending slots 8, the purpose of which will presently appear. Resting upon the ties at the inner sides of the rails, I provide the holding plates 9 which comprise side members 10 adapted to bear against the outer sides of the flanges 3 of the ties, and a bridge plate 11 connecting the said side plates at their inner ends. From the outer edge of

the bridge plate, a flange or lip 12 rises, and this lip or flange 12 is adapted to engage over the base flange of the adjacent rail, as clearly shown in Fig. 2. When the 5 track-engaging or holding plate 9 is to engage a rail between the ends thereof, it terminates at the central vertical web of the rail, as shown at the left in Fig. 2, but, when it is to be employed at a joint between the 10 meeting ends of alined rails, the lip or flange is extended vertically to provide a web-engaging plate or standard 13 provided at its upper edge and at its ends with outwardly projecting lugs 14 adapted to pass 15 through openings 15 provided therefor in the webs of the rails, as clearly shown at the right in Figs. 1 and 2. The side plates 10 of these holding members are constructed with longitudinally extending slots 16, and 20 keys 17 are inserted through the said slots and the slots 8 in the flanges of the tie which may be alined with the said slots 16. The keys 17, as shown clearly in Fig. 5, are wedge shaped and the slots are of correspondingly different lengths so that, when 25 the key is inserted, as shown in Fig. 5, it will have a wedging, binding action upon the end walls of the slots so as to firmly secure the rail-clamping plates upon the 30 ties. If the keys be provided with notched edges, as shown in Fig. 5, the possibility of back motion and consequent loosening thereof will be lessened. To prevent loss of the 35 keys, they are preferably connected to the respective ties by chains or similar elements, as indicated at 18.

In mine track construction, it frequently happens that the laid track terminates a distance from the work less than the length of 40 a rail. This may be due to various causes and is principally due to the fact that, as the work progresses and the mining machine is to be moved forward, the distance to which the track is to be extended is less than the 45 length of a rail. Under these circumstances, it is customary to employ a rail placed upon its side, as shown at 19 in Fig. 6, the head of the said rail engaging between the base flange and the head of the laid rail with the 50 upper side edge of the rail 19 projecting laterally inward beyond the side of the head of the laid rail, as shown at 20 in Fig. 6. As the distance to which this extended rail must project beyond the end of the laid track is 55 relatively short, it has been found that the mine cars may readily ride upon the rail 19 by having the flanges of the car wheels rest upon the projecting upper side face of the head of the said rail 19. To secure the rail 60 in this partly inverted or turned position, the holding plate 9 is shifted inwardly along the tie so that the slots 16 in the side plates of the rail-holding member or clamp will aline with the inner slots 8 of the tie 65 and the key 17 is then inserted through the

said alined slots so that the edge of the lip or flange 12 will bear against the base of the turned rail 19, as shown clearly in Fig. 6, and thereby hold the said rail 19 firmly against the laid track rail. 70

From the foregoing description, taken in connection with the accompanying drawings, it is thought the use and advantages of my improved track fastening will be readily appreciated. The ties may be readily placed in position along the line of the proposed track and will readily penetrate the bed or floor of the mine so that they will be firmly held in place. The rail clamps are merely placed over the ties at the inner sides of the rails and then shoved longitudinally on the ties so that the rail-engaging lips or flanges of the clamps will pass over the base flanges of the rails and the lugs or spurs 14 will pass through the openings 15 when the clamp is 80 located at a rail joint. The spurs or lugs 14 by their engagement with the openings 15 through the webs of the rails positively prevent creeping of the rails and the clamps employed between the ends of the rails may be secured in such firm engagement therewith by the keys that they will supplement and aid the joint clamps to prevent creeping of the rails. The track may be laid very rapidly by the use of my invention and when 85 the mine operations require an abandonment of any particular section or room of the mine, the rails, ties and clamping plates may be very easily and quickly removed and employed at some point in the mine where a new track is to be laid. Inasmuch as there are no bolts or nuts employed in the use of 90 my device, the assembling or disassembling of the several parts may be very easily and rapidly accomplished without the services of specially trained labor or the use of any tools except an ordinary hammer, and the formation of the parts is such that they may be readily formed from sheet metal in a 95 stamping machine. 100

Having thus described the invention, what is claimed as new is:

1. In a mine track fastening, the combination of a tie provided at its ends with inwardly extending overhanging rail-engaging flanges and provided at its sides with depending flanges having longitudinally extending slots therethrough at and near its ends, rail-engaging clamps spanning the tie and provided at their ends with depending side plates bearing against the side flanges of the tie and constructed with slots adapted to aline with slots in the side flanges of the tie and provided at their outer edges with overhanging rail-engaging flanges, and securing keys inserted through the alined slots of the tie and the clamps, said keys being provided along one edge with teeth to engage the opposed wall of a slot and prevent withdrawal of the key. 115 120 125 130

2. In a track fastening, the combination
of a tie, rails provided at their ends with
openings through their webs, inwardly pro-
jecting overhanging lips at the ends of the
5 tie to engage over the base flanges of the
rails, sheet metal clamps spanning the tie
and provided at their outer sides with
flanges to engage over the base flanges of
the rails, some of said plates being provided
10 with vertically extending bearing plates

adapted to bear against the webs of the rails
and provided at their upper edges with out-
wardly projecting lugs to engage through
the openings in the rails, the upper edges
of all the clamps being below the heads of 15
the rails, and means for securing said clamps
in fixed position upon the tie.

In testimony whereof I affix my signature.

CHARLES E. PRICE. [L.S.]
